HINGE CONSTRUCTION FOR UPWARD ACTING DOORS

Stephen S. Katulski, Detroit, Mich., assignor to
 Crawford Door Company, Detroit, Mich., a corporation of Michigan

Application September 7, 1940, Serial No. 355,800

8 Claims. (Cl. 16—137)

This invention relates to a hinge construction especially adapted for use on upward acting garage doors of the sectional type.

Specifically the invention relates to a hinge construction having mating parts held in operative relation by the hub of a door roller.

While the invention will be hereinafter specifically described in connection with a sectional type upward acting garage door, it should be understood that the hinges of this invention are generally adapted for articulately connecting pairs of movable members.

It is highly desirable to mount as much of the hardware as possible on garage doors as the same are assembled at a factory in order that installation of the doors in a garage or building can be speeded up. In garage doors of the sectional type it is therefore highly desirable to provide the door sections with hinges that can have the parts thereof mounted on the door sections at the factory and readily united to hingedly connect the sections at the place of installation of the door.

The present invention now provides hinges composed of mating parts each having a laterally projecting pin segment. The pin segments of each pair cooperate to form the hinge connection and are held in cooperating relation by merely slipping thereover the hub of a door roller.

It is, then, an object of this invention to provide hinges having hinge pin sections held together with the hub of a roller.

A further object of the invention is to provide hinges for upward acting doors having a pair of mating hinge pin sections adapted to be connected together in articulate relation with the hub of a door roller and serve as a support for the roller.

A specific object of the invention is to provide a hinge construction for sectional type upward acting garage doors adapted to be secured to the inner faces of the door sections and having pin portions projecting laterally from the door sections serving both as an articulate connection between the parts of the hinge and as a support for a door roller such as is used in mounting the door sections in the doorway.

Another object is to provide a hinge having a pair of separate elements each equipped with a complementary pivot pin section adapted to be held together by a sleeve so that the pins will rock relative to each other.

Other and further objects of the invention

will of course be apparent from the following detailed description of the annexed sheet of drawings which, by way of example, illustrates a preferred embodiment of the invention.

5. On the drawing:

Figure 1 is an end elevational view of a pair of door sections hinged together with a hinge construction according to this invention and illustrating in dotted lines a door roller cooperating with the hinge parts.

Figure 2 is an end elevational view similar to Figure 1 illustrating the door sections in angular relation.

Figure 3 is an inside elevational view taken 15 along the line III—III of Figure 1.

Figure 4 is a vertical cross-sectional view taken along the line IV—IV of Figure 1.

Figure 5 is an exploded inside elevational view of the mating hinge elements.

20 Figure 6 is an end elevational view, with parts in vertical cross section, taken along the line VI—VI of Figure 5.

As shown on the drawing:

In Figures 1 to 4 inclusive, the reference numerals 10 and 11 designate adjoining door sections or panels for upward acting garage doors. Since these door sections 10 and 11 must tilt relative to each other as the door moves from vertical closed position to horizontal overhead position, the bottom of the door section 10 is centrally recessed as at 10a across the entire length of the section. A long front finger 10b defines one side of the recess 10a while a short rear finger 10c defines the other side of the recess. The finger 10c terminates at a level above the bottom of the finger 10b.

The top of the section 11 has a central rounded bead 11a adapted to fit into the recess 10a of the section 10. The bead 11a extends down 40 to a horizontal shoulder 11b adapted to receive the bottom of the finger 10b when the door is in vertical position as shown in Figure 1. The rear face of the bead 11a terminates in a vertical shoulder 11c adapted to abut against the short finger 10c of the top section 10. The inner face of the door section 11 is beveled inwardly as at 11d to the bottom of the vertical shoulder 11c.

This groove and bead construction on adjoining door panels permits articulation of the door panels relative to each other as illustrated in Figures 1 and 2 and at the same time holds the door panels in alignment across their entire length. In addition, the bead and groove construction provide an efficient weatherstrip seal when the door is in closed vertical position.

In order to connect the door sections 10 and 11 for articulate movement, the present invention provides a pair of mating hinge elements 12 and 13 secured to the door sections and swivelly connected together by means of a hub 14 of a door roller 15 such as is used in mounting the door in operative position in a garage.

The hinge part 12 is composed of an angle bracket having one leg 12a extending over the side edge of the door section 10, and the other leg 12b extending over the inner face of the door. The leg 12b is apertured for receiving screws 16 therethrough to unite the bracket to the door section.

The leg 12a depends beneath the bottom of the leg 12b as shown and has an inclined bottom edge 12c sloping downwardly from the inner face of the door to a point about midway between the fingers 10b and 10c. At this point, the bottom edge of the leg 12a extends horizontally as at 12d toward the outer face of the door.

The bottom portion of the leg 12a carries a pin 17 which projects laterally outward from the leg and is anchored at its inner end by means of a weld such as 18 (Figure 4).

The pin 17 has a semi-cylindrical top wall 17a, a horizontal bottom wall 17b flush with the bottom edge 12d of the leg 12a and an inclined bottom side wall 17c flush with the inside edge 12c of the leg.

The hinge portion 13 is composed of an angle bracket having a leg 13a extending over the side edge of the door section 11 and a leg 13b extending over the inner face of the door section 11. The leg 13b is apertured to receive screws such as 16 therethrough which unite the angle bracket to the door section. The leg 13a over the side edge of the door extends above the leg 13b and has an inclined top edge 13c extending upwardly and outwardly from the inner face of the door section 11 to the longitudinal center of the bead 11a. The top of the leg 13a then continues outwardly along a horizontal line 13d to the outer edge of the leg.

The top 13d of the bracket 13 is adapted to abut against the bottom 12d of the bracket 12 when the door sections are in vertical alignment as shown in Figure 1. Likewise the inclined top portion 13c of the bracket 13 is adapted to abut against a bottom inclined portion 12c of the bracket 12 when the doors are in angular relation as shown in Figure 2.

The leg 13a of the bracket 13 carries a pin 19 with a segmental cylindrical bottom wall 19a, a horizontal top wall 19b flush with the top 13d of the leg and an inclined side wall 19c flush with the inclined portion 13c of the leg. The pin 19 is integrally united with the leg 13a at the junction point between the top edges 13c and 13d thereof by means of a weld 20.

The pins 17 and 19 have the surfaces 17b and 19b thereof in contacting relation when the door is in vertical position as shown in Figure 1, and have the inclined side walls 17c and 19c thereof in contacting relation when the door is in offset or articulated position as shown in Figure 2.

The angular relation between the walls 17b and 17c as well as the angular relation between the walls 19b and 19c of the pins 17 and 19 controls the maximum angular movement between the door sections 10 and 11 in cooperation with the angular relation between the edges 12d and 12c of the bracket 12 and the edges 13d and 13c of the bracket 13.

The hub 14 of the roller 15 is disposed around the segmental cylindrical surfaces 17a and 19a of the pins to hold the pins together for effecting a swivel connection between the hinge brackets 12 and 13.

The hub 14 has a relatively easy fit around the pins 17 and 19 so that the roller can be readily mounted for articulately connecting the hinge brackets.

The roller 15 can be of any known roller construction including a tread portion 15a adapted to ride in the usual door tracks (not shown). As illustrated in Figure 4, the roller 15 is equipped with ball bearings 15b rotatably mounted in a groove 14a provided in the hub 14. The tread portion 15a of the roller 15 thus freely rotates around the hub 14.

The hinge constructions of this invention therefore each comprise a pair of mating angle brackets adapted to be secured to the inner face of adjoining door sections or panels and each having legs or flanges extending from the inner face of the door sections or panels over the side edges of the panels. Each flange or leg carries a laterally projecting pin which serves as a support for the usual door roller of upward acting door constructions and which also serves as means for swivelly uniting the angle brackets.

The hinge brackets of this invention can be united on the door panels or sections at the factory, and the door panels or sections can be shipped with the hardware thereon. The panels or sections are articulately connected as the same are installed on the job by merely sliding the hubs of the door rollers over pairs of mating pins.

The hubs 14 of the door rollers 15 are preferably elongated and project inwardly from the tread portion 15a of the rollers in order that the rollers can slide toward and away from the sides 40 of the door due to variations in alignment of the tracks without moving off of the pins.

While the contacting surfaces of the pins are illustrated as being angularly disposed flat walls, it should be understood that curved surfaces 45 could be used. The angularly disposed flat walls are preferable, however, in that they provide area contact between the pins when the door panels are in vertical alignment or in maximum angular relation. Curved surfaces on the pins, on the other hand, would only provide line contact therebetween during all positions of the pins.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

1. A hinge adapted for uniting door sections of upward acting doors comprising a pair of angle plates each having a leg adapted to be disposed over the inner face of a door section for fixed connection therewith and each having a second leg adapted to be disposed over the side edge of the door section, a pin on each angle plate projecting laterally from the second leg thereof, said pins having opposed surfaces adapted for rocking contact with each other, and a hubbed roller having the hub thereof disposed over said pins for swivelly connecting the angle plates.

2. A hinge construction comprising a pair of angle plates each having one leg thereof adapted to be secured to the inner face of a separate member and the other leg thereof adapted to be

disposed over the side edges of the members, said legs adapted for disposal over the side edges of the members extending beyond the secured legs and having opposed edges adapted to rock on each other, pins projecting normally from said last mentioned legs having longitudinal faces aligned with said edges of the legs, and a sleeve member enveloping both pins whereby said angle plates are held in rockable relation to connect the members in articulate relation.

3. A hinge construction adapted to connect a pair of vertically disposed door sections comprising a plate member secured to a side edge of each door section and having a pin projecting laterally outward from the door sections, the pins of each plate having opposed surfaces adapted to rock over each other, and a door roller slidably mounted around said pins to hold the same in contacting relation and swivelly connect the plates, said pins supporting said roller on the door sections.

4. A hinge construction adapted for uniting a pair of door sections in an upward acting door which comprises a pair of angle plates each having a leg adapted to be disposed over the inner face of a door section for fixed connection therewith and each having a second leg adapted to be disposed over the side edge of the door section, a pin carried by each angle plate for projecting from the side edges of the door sections, and a sleeve disposed over both pins to swivelly unite the angle plates and thereby articulately join the door sections.

5. A hinge adapted for a sectional type door including a pair of adjacent door sections which comprises an angle plate having one leg thereof adapted to be disposed over the side edge of one section and the other leg thereof adapted to be disposed over the inner face of said section, means for uniting said other leg to said section, a second angle plate having one leg thereof adapted to be disposed over the side edge of the

other door section and another leg adapted to extend over the inner face of said other section, means adapted for uniting said other leg of said second angle plate to said other door section,

5 a pin on each angle plate projecting laterally from the leg of the plate which is disposed over the side edge of the door section, said pins having opposed longitudinally extending surfaces adapted to rock on each other, and a hubbed door roller for mounting the door sections having the hub thereof disposed over both pins to swivelly unite the angle plates.

6. A hinge construction comprising a pair of plates having opposed edges adapted to rock on each other, pins projecting from said plates having longitudinal faces aligned with said edges, and a sleeve enveloping said pins to connect the plates in articulate relation.

7. A hinge construction comprising a pair of 20 abutting metal plates having opposed edges each formed by two angularly related end rocking surfaces, a pin extending normally from each plate having two angularly related longitudinal faces aligned with said end rocking surfaces of the plates and having a segmental cylindrical face joining the divergent ends of said angularly related faces, and a sleeve enveloping both pins seated on said segmental cylindrical surfaces thereof to connect the plates in articulate relation whereby the plates can be swung within limits defined by the angularly related end rocking surfaces.

8. A hinge and roller support construction adapted for upward acting doors of the sectional type which comprises a pair of pins adapted to be secured to adjoining door sections and project laterally from the side edges thereof, and a door roller enveloping the pins to rockably connect the same for articulately joining the door sections while serving as a support for the roller.

STEPHEN S. KATULSKI.
